UNITED STATES PATENT OFFICE.

ADAM HOCH, OF PROVIDENCE, RHODE ISLAND, ASSIGNOR TO ADDING AND SUBTRACTING MACHINE COMPANY, A CORPORATION OF RHODE ISLAND.

CALCULATING-MACHINE.

961,961.

Specification of Letters Patent. Patented June 21, 1910.

Application filed February 23, 1909. Serial No. 479,382.

To all whom it may concern:

Be it known that I, ADAM HOCH, a citizen of the United States, residing at Providence, in the county of Providence and State of Rhode Island, have invented certain new and useful Improvements in Calculating Machines, of which the following is a specification.

My invention relates to that class of calculating machines wherein the calculating operations are performed through a slideable ring operated by a stencil or lever, and has for its essential objects, including the ends commonly sought in such structures, speed 10 in calculation, adaptability for calculating high denominations, the provision of a single means for performing the operations of both addition and subtraction; to render it possible to connect and operate a plurality of 15 rings contemporaneously or successively and with a single lever; to enable accumulation in two directions either for addition or for subtraction; and to render it unnecessary to return the lever to original position until the 20 collection of all the digits of the number to be added or subtracted has been collected.

Further objects are simplicity in construction and operation, and accuracy of results.

With the above objects in view and others, 25 as will appear as the description proceeds, the invention comprises the various novel features of construction and arrangement of parts and combination of parts hereinafter described, and set forth in the appended 30 claims.

It will be understood that various changes in form, proportions, size, and minor details of structure may be made without departing from the spirit or sacrificing any of the advantages of the invention.

In the accompanying drawings, which constitute a part of this specification, and in which like reference numerals indicate like parts throughout the views, Figure 1 is 45 a top plan view of a machine embodying my invention showing parts of the housing plate and rings broken away, Fig. 2, a side elevation of the same, Fig. 3, a bottom plan view of the machine, Fig. 4, a diametrical section 50 of the same, Fig. 5, a partial diametrical section of the same enlarged and showing one of the plungers dropped, Fig. 6, a similar section of the same showing all the plungers elevated, Fig. 7, a perspective view of a 55 plunger, and Figs. 8, 9, 10 and 11, sections

on lines *v v*, *w w*, *x x*, and *y y* respectively of Fig. 3.

In its present embodiment, my machine comprises a circular base or frame, 1, provided with a flat marginal rim, 2, and having a plurality of rubber feet, studs, or other supporting means, 3, upon its bottom surface. The face of the rim is graduated throughout half its length to form a semi-circular index, 4, comprising upon its inner margin a series of lines, 5, numbered consecutively from 1 to 99 from right to left, and upon its outer margin a second series of lines, 6, alternating with the first series of lines, and numbered successively from left to right up to 99. The lines of series 6 as will be later described, are employed in subtraction, and the series 5 in addition calculations. The rim, 2, and the adjacent portion of the frame are provided with transverse slots, 7 and 8, located diametrically opposite each other at the ends of the index scale, 4. The upper face of the frame is provided adjacent the rim with a broad annular channel, 9, and with three inner concentric annular seats, 10, 11 and 12, provided respectively in their bottom portions with grooves, 13, 14 and 15, and separated respectively from the channel, 9, and from each other by the shoulders, 16, 17 and 18. Adjacent the shoulders, the seats are respectively provided with depressions, 20, 21 and 22. Upon the shoulder, 16, is fixed by screws, 24, or otherwise, a semi-circular index plate, 25, provided with 100 radially disposed pointed teeth, 26, forming intermediate indentations upon its periphery, and extending the length of the scale, 4. The indentations are in radial alinement with the index lines, 4 and 5. Rotatably mounted in the seats, 10, 11, and 12, respectively, are the numeral or dial rings, 28, 29, and 30, each provided with 200 peripheral teeth and indentations, 31, 32, and 33, extending over the depressions, 20, 21 and 22. At diametrically opposite points upon the bottoms of each ring are two carrying pins, 34, 34, 35, 35, and 36, 36, extending into the grooves, 13, 14 and 15. These numeral rings are each provided upon its upper face with a series of numerals, 37, 38 and 39. These numerals in each case run from 00 to 99 upon one-half of the ring, and are repeated upon the other half of the ring. Each numeral corresponds to one of the 200 indentations. The denominations on ring 110

30 are units and tens; on ring, 29, hundreds and thousands; on ring 28, ten thousands and hundred thousands. The carrying pins on each ring are located immediately below and between the index numerals, 60 and 99, and are purposed to set the carrying mechanism.

10 Fixed by screws, 41, or otherwise to the upper face of the frame is a housing plate, 42, flush with the top of rim, 2, and cut away along a portion of its margin as at 43, to expose the teeth, 26, of the index plate, 25, and has semi-circular slots, 44, 45 and 46, above the ring teeth, 31, 32 and 33 respectively. It is further provided with a row of reading openings, 48, 49, 50 and 51; the last three being located over rings 28, 29 and 30. 15 An operating arm, 52, is closely mounted above the plate, 42, upon the upper end of a retaining stud, 53, which passes through apertures, 54 and 55, in the centers of the plate, 42, and frame, 1, respectively, and is provided upon its upper end with a screw head, 55', and at its lower portion, with 20 screw threads, 56, to receive a milled retaining nut, 57. The operating arm is longitudinally recessed as at 59 and 60, and provided with three vertical openings, 61, 62, 63, to accommodate certain operating mechanism now to be described. One side of the outer end of the arm is cut away to receive 25 a removable side plate, 64, fixed by screws, 65, to the arm, with which, for the purposes of further description, it will be treated as an integral part. Slidably mounted in the opening, 59, in the arm is a plunger cam plate, 68, whose inner end, is contacted with a slideable pin, 69, pressed by a spring 70, located in the recess, 60. The outward movement of the plate, 68, is limited by one of the screws, 65, against which its outer end abuts. The upper and lower end margins of this plate are provided respectively with inclined teeth, 72 and 73; and its body portion, with a row of three cam slots, 74, 75 and 76. The outer slot, 74, has a downwardly inclined intermediate portion, 77, and horizontal upper and lower end portions, 78 and 79'. The intermediate slot, 75, has corresponding portions, 80, 81, and 82; the portion, 81, being shorter than portion, 78, and portion, 82, longer than portion 79'. The inner slot, 76, has a downwardly inclined portion, 83, and an extended horizontal lower end portion, 84. The latter is longer than the portion 82.

50 Vertically slideable in the openings, 61, 62 and 63, are plungers, 86, 87 and 88 respectively. These plungers, which are similar to each other, are each provided with vertical slots, as at 89, in Fig. 7, to permit passage therethrough of the plate, 68, and have reduced pointed lower ends, 90. Transversely disposed supporting pins, 91, 92 and 93, in the respective plungers, register in slots, 74, 75

and 76. Pivoted upon a pin, 95, in the outer end of the arm, 52, is a vertical operating lever, 96, provided upon its upper end with a handle, 97. Pivoted to a stud, 98, in the lever is a pawl, 100, adapted to engage the teeth, 73, of the plate, 68. The pawl is provided with a lug or finger, 101, adapted to rest against the front of a pin, 102, fixed in the lever arm, 52. This lever pawl is upwardly pressed into engagement with the teeth, 73, by a wire spring, 104, one of whose ends extends beneath the pawl arm, and whose other end is fixed to a pin, 106, upon the lever, 96. Pivoted upon a pin, 107, in the arm, 52, above the plate, 68, is a detent, 108, normally engaging the teeth, 72, and provided with an upturned finger, 109, resting against a pin, 110, in the lever, 96, and pressed by a spring, 111, upon the arm. A single outward movement of the handle, 97, through the pawl, 100, advances the plunger cam plate, 68, the distance of a tooth, 73, against the presser of spring, 70, at which point the detent, 108, engages its next tooth, 72, and prevents the return of the plate, 68. 10 This described advance of the latter plate by virtue of the inclined portion of the cam slot, 76, depresses the plunger, 88, throwing the point of the latter into engagement with the teeth of the inner numeral ring, 30. A 15 repetition of the described movement engages, by a like operation of parts, the plunger, 87, with the teeth of the intermediate ring, 29. A second repetition of the movement results in engaging the plunger, 86, 100 with the teeth of outer ring, 28. The three plungers are thus successively depressed by three independent movements of the handle in an outward direction. All the plungers are simultaneously elevated by a single 105 movement of the lever handle inwardly which disengages the pawl and detent from their respective teeth and permits the plate, 68, to shoot outwardly under the pressure of its spring. The lateral swing of the handle, 97, imparts a circular movement to the arm, 52, which, when connected to any numeral ring, rotates the same a corresponding distance.

To index the movement of the arm, 52, there is in its end above the graduations of the scale, 4, an index pin, 112. In front of this pin, upon the arm, is a lug, 113, extending downwardly into the channel, 9, which serves as a bearing for the free end of the 110 arm.

115 Vibration of the lever, 96, operates other mechanism. The bottom of the frame has a marginal rim or boss, 115, cut away at opposite points, 116 and 117, which are bridged by plates, 118 and 119. A horizontal slideable plate, 120, is provided with an oblong horizontal, and an oblong vertical opening, 121, and 122, and with flat integral lateral arms, 123 and 124, in alignment with each other, passing 125

over the retaining plates, 118 and 119, and having upon their respective ends vertical lugs, 125 and 126, which correspond in shape with the sectional contour of the rim, 2. The 5 plate, 120, has also upon its lower portion inwardly directed lateral lugs, 127 and 128, contacting with the inner edges of two levers, 129 and 130, pivoted at their upper ends to the base by screws, 131 and 132, and 10 connected at their lower ends by a spiral spring, 133. Projections, 134, upon the frame, serve as stops for the inward movement of the levers, 129 and 130. The end of a hub or projection, 135, upon the frame 15 rounding the pin, 53, extends through the opening, 121. Upon this hub above the plate, 120, is pivoted intermediate its ends a flat oblong oscillating or vibrating cam plate, 137, disposed at right angles to the 20 slide plate, 120, and provided near its lower end with a pin, 138, registering in slot, 122, and provided in its opposite end with three transversely disposed cam slots, 139, 140, 141, substantially parallel with each other, 25 and each downwardly inclined toward both ends. The described mechanism, actuated by lever, 96, drives or operates the accumulating mechanism.

Fixed to the plate, 137, by screws, 143 and 30 144, or otherwise are two oppositely disposed lateral arms or levers, 145 and 146, provided upon their respective ends with receding cam plates, 147 and 148, which, together with the arms, serve as cam levers. 35 The operative portions of the cam plate, 147, comprise inwardly directed fingers, 149, provided with interspaced beveled ends, 150, forming a segmental slot, 152. The plate, 148, has similar fingers, 153, with beveled 40 interspaced ends, 154, and forming a segmental slot, 155. Fixed to the bottom of plates, 147 and 148, are bearing or lifter plates, 156 and 157, respectively projecting across the slots. 45 Adjacent the plates, 147 and 148, the bottom of the base is provided with integral projections or bosses, 158 and 159, in which are openings, 160 and 161, respectively extending through the base, which receive as 50 a sliding fit the stems or rods, 162 and 163 of circular receding cams, 164 and 165, each provided with inclined or conical upper and lower faces, 166, 167 and 168, 169. These cams, which are upon the lower ends of the 55 stems, are normally supported by the bearing or lifter plates, 156 and 157. Fixed to the upper end of rod, 162, is a star segment or disk, 171, provided with a tooth, 172 and a marginal cavity, 173. A similar segment, 174, is fixed to the end of rod, 163, and has a similar tooth, 175, and cavity, 176. Loose upon the rods, 162 and 163, respectively, and resting upon the upper face of the frame, are segment gears, 178 and 179, 60 each provided with a fixed vertical pin, 180,

181, adapted to pass loosely through the cavity, 173 and 176. The portions of the upper face of the frame beneath and adjacent the segmental gears are recessed as at 183 and 184, to form flat bearing surfaces 70 below the plane of the numeral rings for the accumulating mechanism. When the rods, 162 and 163, are in normal elevated position, the star segment teeth, 172 and 175, are respectively in the path of the pins, 35, of the 75 ring, 29, and of the pins, 36, on the ring, 30. The vibrations of cam plates 147 and 148, reciprocate the star segments, 171 and 174, into and below the path of pins, 35 and 36. The circular movement of the numeral rings, 80 29 and 30, in either direction, when their pins engage the cam segments, imparts movement to the segment gears, 178 and 179, in a corresponding direction.

Reference will now be made to the accumulating mechanism. Pivoted upon pins, 186 and 187, and resting upon the recessed upper face of the frame at 183 and 184, are segmental accumulation plates or disks, 188 and 189, respectively, provided upon a portion of their margins with gear teeth, 190 and 191, meshing with segment gears, 178 and 179. The plates are also respectively provided with V-shaped marginal recesses, 192 and 193, adapted to receive the 95 V-shaped ends of plungers, 195 and 196, slidably mounted in tubes, 197 and 198, soldered, threaded, or otherwise fixed in the base, and pressed into the recesses by springs, 199 and 200 in the tubes. The 100 springs are held in position by screws or plugs, 201 and 202, in the ends of the tubes. The plungers and springs may be mounted in recesses in the frame itself, if preferred. Pivoted at one end by a pin, 204, to the face 105 of the segment, 188, and 189, respectively, provided upon a portion of their margins with gear teeth, 190 and 191, meshing with segment gears, 178 and 179. The plates are also respectively provided with V-shaped 110 marginal recesses, 192 and 193, adapted to receive the V-shaped ends of plungers, 195 and 196, slidably mounted in tubes, 197 and 198, soldered, threaded, or otherwise fixed in the base, and pressed into the recesses by 115 springs, 199 and 200 in the tubes. The springs are held in position by screws or plugs, 201 and 202, in the ends of the tubes. The plungers and springs may be mounted in recesses in the frame itself if preferred. Pivoted at one end by a pin, 204, to the face 120 of the segment, 188, at a point opposite the teeth, 190, and near the recess, 192, is an accumulating lever, 205, provided upon the upper face of its free end with a tooth, 206, 125 and, at a corresponding point upon its lower face, with a pin or projection, 207, passing loosely through an oblong opening, 208, in the frame and through the cam slot, 140. A second accumulating lever, 210, is pivoted 130

4
by a pin, 211, to segment plate, 189, at a point upon its upper face opposite the teeth, 191, and has upon its free end an upright tooth, 212, and a downwardly directed pin, 5 213, traversing an opening, 214, in the frame and cam slot, 189. A third lever, 215, is pivoted at one end, 216, to the upper face of the base below the lever, 205, and has upon its free end the upper tooth, 217, and 10 lower pin, 218. The latter traverses a frame opening, 219, and the cam slot, 144. The lever teeth, 212, 206, and 217, are respectively in the plane of and adjacent the teeth and indentations of the numeral rings, 28, 29 15 and 30, so that a lateral movement of the cam plate, 137, communicated through the lever pins, 213, 207 and 218, causes the latter to move vertically and to engage or disengage the lever teeth and ring teeth.

20 The accumulation levers, 205, 210, are horizontally moved to positions opposite their proper ring teeth preparatory to engagement therewith, by means of the numeral ring pins, 35 and 36, which actuate, through 25 segment gears, 178 and 179, the plates, 188 and 189. The pressure of the ring pins in this operation is sufficient to unseat the bolts, 195 and 196, from their cavities, 192 and 193. These bolts temporarily lock the plates 30 in their original or moved positions. After the accumulation levers, 210, and 205, have been advanced the distance of a single tooth as described, a lateral swing of the cam plate, 137, in whose cam slots, 139 and 140, 35 the lever pins register, forces or drives the accumulation lever teeth downwardly into engagement with their adjacent ring teeth, and then rearwardly into original radial alignment with each other and with the 40 tooth of the non-cumulating vibrating lever, 215. The combined downward and rearward movement, therefore, advances the rings, 28 and 29, the distance of one tooth respectively relatively to the ring, 30. A 45 return swing of the plate, 137, to normal or central position again elevates all the levers out of engagement with the numeral rings. In performing addition the plate, 137, is swung to the right, and in subtraction, 50 to the left of its normal central position, as viewed in Fig. 1. The operations of the accumulating mechanism in addition and subtraction are identical except that the movements are in opposite directions. The 55 oscillation of the plate, 137, is produced by the movement of the lever, 96, in the operating handle whose operation will be herein-after described which pulls the slide plate, 120, laterally to its limit of movement in one 60 direction, and then, releasing the plate, permits one of the slide levers, 129 or 130, under the action of spring, 133, to return the plate, 120, again to central position.

It may sometimes be convenient in calculating numbers aggregating numerous digits

to employ means for carrying from the outermost numeral ring. For this purpose, the following indicator is provided. Loosely traversing the frame, 2, and housing plate, 42, near the ring, 28, is a pin, 222, having a 70 knurled head, 223, upon its upper end. Fixed to this pin is a numeral disk, 225, resting upon the base below the reading opening, 48, of the housing plate, and indexed from 0 to 9. Fixed to the lower portion of this pin by a nut, 226, upon its threaded end or otherwise is a gear, 228, which meshes with a pinion, 229, fast on a pin, 230, rotatably mounted in the frame. This pin has fast to its upper end a star 80 wheel, 231, in the path of the pins, 34, of the numeral ring, 28. The passage of one of the latter pins in contact with the star wheel actuates the disk, 225, the distance of one numeral. For preventing accidental or 85 overrotation of the disk is a star wheel, 232, fixed to the lower end of the pin, 230, between whose teeth rests the bent end, 233, of a spring rod, 234, fixed at its opposite end by screws, 235 and 236, in the frame. 90

To perform additive calculations the operations are as follows: The zero points of all the numeral rings are originally beneath their respective reading openings, and the operating arm, 52, is in the position shown 95 in Fig. 1, with its side abutting against a stop pin, 238, in the frame near the edge of the housing plate and its lever in line with the lug, 125, of the sliding plates. The handle, 97, of the operating lever is in vertical position, and the plungers, 86, 87 and 88, elevated. The arm, 52, is swung to a position in which its indicator pin, 112, is above the particular line of the additive graduation series, 5, upon the fixed index 100 whose numeral is the same as that which is to be added to the units and tens columns, whereupon the handle, 97, is outwardly vibrated to insert the plunger, 88, into engagement with the teeth of the ring, 30. The 105 handle from this point is next swung in either convenient direction to soonest reach with the index pin, 112, the numeral graduation of the fixed index which is the same as the hundreds and thousands digits to be 110 added, and the handle again outwardly vibrated to engage the plunger, 87, with ring, 28. If the number to be added is of still greater denomination the described operation of the lever handle is repeated, still 115 without returning arm, 52, to original position, and the ring, 28, engaged with plunger, 86. After the whole number has thus been collected, the arm is rotated back to original position, by which movement the pins, 36, 120 35 and 34, upon the bottoms of the movable rings set up the accumulation levers, 215, and turn the star wheel 231, as already described. The lever handle is then vibrated 125 inwardly which disengages the plungers 130

from the rings as described. This inward vibration of the handle forces the lower end of the lever, 96, outwardly against the lug, 125, thus sliding the plate, 120 laterally to 5 complete the carrying operations.

In the process of subtraction the same movements are performed by the handle, 97, as those described in additive operations except that the original and setting up position of the operating arm is against a stop pin, 239, and in front of lug, 126, diametrically opposite the position shown in Fig. 1. In subtraction, however, the graduation series, 6, is employed instead of series, 5. 10 Thus, the movements are exactly like those of addition, but in an opposite direction, and the use of complementary numbers in subtraction calculations is eliminated.

Obviously the greater or less number of 20 numeral rings and their corresponding accumulation members may be embodied in my machine, and the indicator be omitted, without departing from the spirit of my invention.

25 I do not desire to be limited to the exact details of construction shown and described, for obvious modifications will occur to a person skilled in the art.

What I claim is,

30 1. In a calculating machine, the combination with the frame, of a numeral ring slidably mounted upon the frame, an operating arm pivotally mounted in the frame concentric with the ring, a plunger slidably mounted in the arm adapted to engage the ring, and means in the arm adapted to actuate the plunger.

2. In a calculating machine, the combination with the frame, of a numeral ring upon 40 the frame, an arm pivotally mounted upon the frame concentric with the ring, a plunger slidably mounted in the arm and adapted to engage the ring, and slidable means in the arm for actuating the plunger.

45 3. In a calculating machine, the combination with the frame, of a numeral ring upon the frame, an arm pivotally mounted upon the frame concentric with the ring, a reciprocating plunger in the arm adapted to engage the ring, and means in the arm for reciprocating the plunger.

4. In a calculating machine, the combination with the frame, of a numeral ring upon the frame, an arm pivotally mounted upon 55 the frame concentric with the ring, a reciprocating plunger in the arm adapted to engage the ring, and slidable means in the arm for reciprocating the plunger.

5. In a calculating machine, the combination with the frame, of a plurality of numeral rings slidably mounted in the frame, an operating arm pivotally mounted upon the frame, a plurality of plungers slidably mounted in the arm above the rings and 60 adapted to engage the same, and means in

the arm for selectively operating the plungers.

6. In a calculating machine, the combination with the frame, of a plurality of numeral rings mounted in the frame, an operating arm upon the frame, a plurality of plungers in the arm above the several rings and adapted to engage the same, and means in the arm for operating the plungers in 70 succession.

7. In a calculating machine, the combination with the frame, of a plurality of numeral rings upon the frame, an operating arm upon the frame, a plurality of plungers in the arm above the several rings and adapted to engage the same, and means in the arm for operating the plungers independently of each other. 75

8. In a calculating machine, the combination with the frame, of a stationary index 85 upon the frame provided with two concentric reversely arranged series of graduations alternating with each other, independent numeral rings rotatably mounted upon the frame concentric with the index and rotatable 90 and movable in opposite directions and provided with graduations, and means upon the frame for simultaneously rotating the rings.

9. In a calculating machine, the combination with the frame, of an index upon the frame provided with reversely arranged series of graduations, independent numeral rings rotatably mounted upon the frame concentric with the index and rotatable in 100 opposite directions each ring being provided with a single continuous series of graduations, and means upon the frame for rotating the rings. 95

10. In a calculating machine, the combination with the frame, of a stationary 105 curved index upon the frame and provided with two concentric series of graduations reversely arranged as to denominative values, a plurality of numeral wheels rotatably mounted upon the frame concentric with the index and each provided with a single series of graduations arranged in a circle. 110

11. In a calculating machine, the combination with the frame and numeral rings upon the frame, of an operating arm pivotally mounted upon the frame concentric with the rings, a longitudinally disposed cam plate slidably mounted in the arm, a plurality of plungers slidably mounted in the arm and engaging the cam plate, spring means in the arm for sliding the plate in one direction, and an operating lever pivotally mounted in the arm for moving the 120 plate in the opposite direction. 115

12. In a calculating machine, the combination with the frame and numeral rings upon the frame, of an operating arm pivotally mounted upon the frame concentric 130

with the rings, a cam plate provided with a plurality of downwardly inclined cam slots, a plurality of plungers slidably mounted in the arm, supporting pins in the plungers 5 registering in the cam slots, spring means in the arm for moving the plate in one direction, and pivotal means in the arm for moving the plate in the opposite direction.

13. In a calculating machine, the combination with the frame and numeral rings, of an operating arm pivotally mounted upon the frame concentric with the rings, a cam plate slidably mounted in the arm and provided with inclined teeth upon its 10 upper and lower margins, a plurality of plungers slidably mounted in the arm and engaging the cam plate, a spring in the arm pressing against one end of the cam plate, an operating lever pivotally mounted in the 15 arm adjacent the other end of the cam plate, means upon the lever for engaging the teeth upon the lower margin of the plate, and means upon the lever for engaging the teeth upon the upper margin of the plate.

14. In a calculating machine, the combination with the frame, of a plurality of numeral rings upon the frame, an operating arm pivotally mounted upon the frame concentric with the rings, a plurality of plungers 20 slidably mounted in the frame adapted to engage the rings, means in the arms for successively depressing the plungers into engagement with the rings, and means in the arm coöperating with the depressing 25 means for simultaneously elevating the plungers out of engagement with the rings.

15. In a calculating machine, the combination with the frame and numeral rings, of an operating arm mounted upon the 30 frame concentric with the rings, a longitudinally slidably cam plate mounted in the arm provided with two sets of teeth, a plurality of plungers slidably mounted in the arm and operatively connected with the 35 cam plate, a spring in the arm for outwardly pressing the cam plate, an operating lever in the arm adjacent the cam plate, a pawl upon the lever adapted to engage one set of teeth, and a detent upon the lever adapted 40 to engage the other set of teeth.

16. In a calculating machine, the combination with the frame, of numeral rings 45 slidably mounted upon the frame, accumulating mechanism upon the frame operatively connected with the rings, and means for operating the rings and actuating the accumulating mechanism.

17. In a calculating machine, the combination with the frame, of numeral rings 50 rotatably mounted upon the frame, accumulating mechanism mounted in the frame, means for rotating the rings, means operated by the rings for setting the accumulating mechanism relatively to the rings, and 55 means independent of the rings for driving

the accumulating mechanism after the setting operation.

18. In a calculating machine, the combination with the frame, of numeral rings 70 slidably mounted in the frame, an operating arm pivotally mounted in the base concentrically with the rings, an accumulating mechanism in the base operatively connected with the rings and means in the operating handle for actuating the accumulating mechanism.

19. In a calculating machine, the combination with a plurality of numeral rings, of an accumulating mechanism for each ring, means actuated by the numeral rings 80 for setting the accumulating mechanisms relatively to the rings, and means for simultaneously operating the accumulating mechanisms after the setting operation.

20. In a calculating machine, the combination with the frame, of a plurality of numeral rings slidably mounted upon the frame, a vibratory cam plate pivotally mounted upon the frame concentric with the rings and provided with cam slots, accumulation plates pivotally mounted upon the frame, accumulation levers pivoted to the accumulation plates and movable toward and away from the rings, teeth upon the levers adapted to engage the rings, pins 90 upon the levers registering in the cam slots and actuated by the cam plate, operative connections between the rings and accumulation plates, and means for vibrating the cam plate.

21. In a calculating machine, the combination with the frame, of numeral rings slidably mounted in the frame and provided with indentations, pins upon the rings, star disks in the paths of the numeral pins, rods rotatably mounted in the frame and to which the star disks are fixed, gears loose upon the rods and connected with the star disks, accumulating plates pivotally mounted upon the frame provided with teeth engaging the gears, and provided with recesses, plungers yieldingly mounted in the frame registering in the recesses, accumulating levers mounted pivotally upon the accumulating plates, teeth upon the levers adapted to enter the indentations of the numeral rings, and means for moving the levers.

22. In a calculating machine, the combination with the frame, of numeral rings 120 slidably mounted in the frame, pins upon the rings, rods slidably mounted in the frame at right angles to the plane of the rings, star disks fixed to the tops of the rods and normally in the paths of the ring pins, gears loose upon the rods and resting upon the frame, accumulating mechanisms engaged by the gears, receding cams upon the lower ends of the rods, a vibratory plate pivotally mounted upon the frame concentric with the 125

130

rings, arms upon the plate, cam plates upon the arms adapted to contact with the cams when the pivoted plate is vibrated, and means for vibrating the pivoted plate.

- 5 23. In a calculating machine, the combination with the numeral rings, ring pins, and accumulating mechanisms, of setting mechanisms, each setting mechanism comprising a rod, a cam upon the rod, a star disk, fixed 10 to the rod and provided with a cavity, a gear loose upon the rod, and a pin upon the gear extending loosely through the cavity.
- 15 24. In a calculating machine, the combination with the numeral rings, ring pins, and accumulating mechanisms, of setting mechanisms normally connecting the ring pins and accumulating mechanisms, and means for disconnecting the setting mechanisms from the ring teeth.
- 20 25. In a calculating machine, the combination with the frame provided with a hub, of a vibratory cam plate pivotally mounted intermediate its length upon the hub, a plate slidably mounted in the frame at right 25 angles to the cam plate and provided with

an oblong horizontal opening into which the hub extends, and with an oblong vertical opening, a pin upon the cam plate registering in the vertical opening, levers pivoted at one end upon the frame at opposite sides 30 of the hub, a spring connecting the free ends of the levers, lateral lugs upon the slide plate in contact with the levers, and projections upon the frame also in contact with the levers.

35

26. In a calculating machine, the combination with the frame, of a numeral ring slidably mounted upon the frame, a pin upon the ring, a star wheel in the path of the ring pin, a pin loose in the frame and to 40 which the star wheel is fixed, a pinion upon the second pin, a gear meshing with the pinion and fixed to a third pin, and a numeral disk also fixed to the third pin.

In testimony whereof I have affixed my 45 signature in presence of two witnesses.

ADAM HOCH.
